CAP

Nancy Kuenzig, Kew Gardens, N.Y., assignor to I. B.
Kleinert Rubber Company, New York City, N.Y., a corporation of New York

Filed Jan. 13, 1964, Ser. No. 78,163

Term of patent 14 years

(Cl. D3—13)

I claim:

An ornamental design for a cap, as shown and described.
